[57] **CLAIM**

The ornamental design for a combined truss strut and hub connector for dome structures, as shown and described.

DESCRIPTION

FIG. 1 is a perspective view of the combined truss strut and hub connector for dome structures of my new design;

FIG. 2 is an enlarged top plan view thereof;

FIG. 3 is a side elevation view of FIG. 2 the opposite side being a mirror image thereof;

FIG. 4 is a bottom plan view of FIG. 2;

FIG. 5 is a left end elevation view of FIG. 2;

FIG. 6 is a right end elevation view of FIG. 2; and

FIG. 7 is a sectional view taken along line 7—7 of FIG. 1.
